UNITED STATES PATENT OFFICE

91,602

DESIGN FOR A PLATE OR SIMILAR ARTICLE

Yukio Buma, New York, N. Y., assignor to Morimura Bros. Inc., New York, N. Y., a corporation of Japan

Application November 26, 1932, Serial No. 46,181

Term of patent 7 years

To all whom it may concern:

Be it known that I, YUKIO BUMA, a subject of the Emperor of Japan and a resident of the city, county and State of New York, have invented a new, original, and ornamental Design for a Plate or Similar Article, of which the following is a specification, reference being had to the accompanying drawing, forming part hereof.

The drawing is a plan view of a plate showing

my new design, a repeat unit of which is contained between the dotted lines. Said unit is repeated about the circumference of the plate in the relation indicated by the extension of the detailed showing beyond the dotted lines.

I claim:

The ornamental design for a plate or similar article, as shown and described.

YUKIO BUMA.
